UNITED STATES PATENT OFFICE.

HARRIETTE ROBERTS, OF OSKALOOSA, IOWA.

CHICKEN BROODER.

Application filed July 30, 1924. Serial No. 729,153.

My invention relates to chicken brooders, and has for its object to provide a construction in which the products of combustion and obnoxious and dangerous gases will be effectively carried off and the air in the hover kept fresh and pure, and in which also the maximum heat will be obtained and distributed from the heating medium.

To the accomplishment of the foregoing and such other objects as may hereinafter appear the invention consists in the features hereinafter particularly described and then sought to be clearly defined by the claims, reference being had to the accompanying drawings forming a part hereof.

The drawing illustrates a vertical central section through the brooder, with an annular radiator in full lines.

In the drawings the numeral 1 designates a cone-shaped dome or housing of suitable material provided with legs 2 by which it may be supported upon a floor or suitable base at a suitable distance above the same and having at its base a hanging apron or curtain 3 which may be slotted or separated at suitable intervals for the easy egress and ingress to and from beneath the dome or housing, the interior of which constitutes the hover for the chicks.

Within the cone or housing there is supported by brackets 4, or otherwise, a cone-shaped member 5 having an annular or ring-like base 6 and consisting of a number of parallel passage-ways 7 communicating one with the other at one end, as illustrated at 8, the innermost passageway having depending from its upper end a tubular neck 9 from which is supported a hollow cap member 10 formed preferably with vertical side walls 11 and converging top 12 and within which is suitably suspended, say by a rod 13, a conical deflector 14, the walls of which are formed with perforations 15. The outermost passage-way opens at its upper end into a flue 16 which may be provided with a damper 17 to control the escape of outflowing currents traversing the parallel communicating passage-ways mentioned. Beneath the cap 10 there is suitably supported an oil burner or lamp 18 to which oil under control by a valve 19 is supplied from a suitable oil reservoir 20, the chimney 21 of the lamp extending up into the cap 10 as illustrated. The products of combustion from the lamp or heater discharge into the cap 10 and are deflected by the bell shaped de-

flector so as to be directed between it and the inclined top of the cap and out through the neck 9 into the upper end of the innermost passage-way 7 and from the same, at its lower end, into the outermost passage-way 7 and from the upper end of the same into the flue 16. From this flue the escaping products pass into an exit pipe 22 which discharges into the lower part of an annular shaped drum 23 and from the upper portion of the same into a pipe 24 to which is attached a discharge pipe 25 leading to a proper point outside of the compartment or structure in which the brooder is located. The drum 23 affords large radiating surface, and air is free to circulate through the central air space 26 of the drum formed by the annular construction of the drum. While it is preferred to use the annular drum as a part of the brooder because of the advantages arising from its use yet it can be omitted and the flue 16 extended directly to make connection with the final discharge pipe 25, and the advantages of the other features of construction retained.

Under the particular construction and arrangement of passage-ways described a strong circulation of air and the products of combustion is obtained so that all injurious gases are expeditiously drawn out of the brooder and at the same time a good circulation of pure air obtained in the hover and at a temperature best calculated for brooding purposes as the large heat radiating surface obtained by the described construction promotes the best results and at the least expenditure of fuel.

I have illustrated and described with particularity the preferred details but changes may be made therein without departing from the scope of the invention as sought to be defined by the appended claims.

Having described my invention and set forth its merits what I claim is:

1. A brooder comprising in combination a cone shaped dome, a plurality of concentrically positioned walls forming a cone shaped heat circulating chamber spaced from said dome, a heat spreading partition member within said cone shaped heat circulating chamber, the upper end of said heat circulating chamber being connected with an exit flue and the other end of said heat circulating chamber being provided with a downwardly depending collar portion, said collar portion having an annular skirt con-

nected by a conical wall with said heat circulating chamber, a source of heat positioned beneath said annular skirt, and a conical shaped heat deflecting surface positioned 5 within said downwardly depending collar portion for securing uniform distribution of heat in said heat circulating chamber.

2. A brooder comprising in combination a 10 heating device, a plurality of conical shaped hood members, one of said hood members forming a housing for the others of said hood members, a pair of said hood members being closed at their lower ends forming a 15 heat circulating chamber, an exit flue connected to the top of one of said last named

hood members and a depending collar member connected with the inner periphery of the other of said pair of hood members immediately below said exit flue, a source of heat located below said collar member, and a pair of conical shaped members disposed in the path of travel of heat from said source, one of said conical shaped members being situated in said collar member and the other of said conical shaped members being 20 located in said heat circulating chamber for securing uniform distribution of heat throughout the brooder.

In testimony whereof I affix my signature.
HARRIETTE ROBERTS.
